CLAIM

The ornamental design for an optical reading device, as shown and described.

DESCRIPTION

FIG. 1 is a top perspective view of an optical reading device.

FIG. 2 is a front view of the optical reading device shown in FIG. 1.

FIG. 3 is a rear view of the optical reading device shown in FIG. 1.

FIG. 4 is a first side view of the optical reading device shown in FIG. 1.

FIG. 5 is a second side view, opposite that of FIG. 4, of the optical reading device shown in FIG. 1.

FIG. 6 is a bottom view of the optical reading device shown in FIG. 1; and,

FIG. 7 is a top view of the optical reading device shown in FIG. 1.

The portions depicted in broken line are for illustrative purposes only and form no part of the claimed design.
